UNITED STATES PATENT OFFICE.

WILLIAM R. WATKINS, OF WOODLAWN, ALABAMA.

COLLAPSIBLE SHIPPING AND STORAGE BOX.

1,208,420.

Specification of Letters Patent. Patented Dec. 12, 1916.

Application filed August 1, 1913. Serial No. 782,519.

To all whom it may concern:

Be it known that I, WILLIAM R. WATKINS, a citizen of the United States, residing at Woodlawn, in the county of Jefferson and State of Alabama, have invented 5 certain new and useful Improvements in Collapsible Shipping and Storage Boxes; and I do hereby declare the following to be a full, clear, and exact description of the 10 invention, such as will enable others skilled in the art to which it appertains to make and use the same.

This invention relates to new and useful 15 improvements in collapsible boxes or crates, and as its principal object contemplates the provision of a device of this character which may be cheaply manufactured, will be durable and efficient in its operation and may be expeditiously used in shipping or storing 20 goods or articles of any kind or nature.

The above and additional objects are accomplished by such means as are illustrated in the accompanying drawings, described in the following specification and then more 25 particularly pointed out in the claim which is appended hereto and forms a part of this application.

With reference to the drawings, wherein 30 I have illustrated the preferred embodiment of my invention as it is reduced to practice, and throughout the several views of which similar reference numerals designate corresponding parts: Figure 1 is a perspective view illustrating the various folding elements of the box in assembled relation. Fig. 2 is a perspective view illustrating the elements in various open and closed positions. Fig. 3 is a section on the line 3—3 of 35 Fig. 1. Fig. 4 is a transverse section on the line 4—4 of Fig. 1. Fig. 5 is a perspective view illustrating the various elements of the box in folded relation. Fig. 6 is a detail view of the preferred form of the latch hinge. Fig. 7 is a detail perspective view of the hinge shown in Fig. 6, in a different position.

Proceeding now to the description of the drawings, the preferred embodiment of this invention includes a bottom wall 10, a pair 40 of end walls 11 and 12, a pair of side walls 13 and 14 and a top 15. The walls 13 and 14 consist of hinged sections to enable compact folding of the box. The bottom wall 10 is equipped with a pair of longitudinally 45 extending bars 16 and 17, the terminals of which project slightly beyond the end edges

of the member 10. The purpose in extending the terminals of the members 16 and 17 beyond the end of the bottom wall 10 is to 50 permit the hinging of the bars 18 and 19 of the end wall 11, and the bars 20 and 21 of the end wall 12 to the members 16 and 17, as will be readily observed by reference to Fig. 3. The side wall 13 is hinged as at 55 22 to the upper face of the bottom wall 10 and the sections forming the same, designated 22^a and 22^b when in folded position, lie flat on the bottom wall. The other side wall designated as an entirety by the numeral 14 is formed in two sections 23 and 24 which are hingedly connected as at 25 60 and are designed to fall one upon the other when the box collapses, as will be herein-after more fully described. The top 15 is hinged to the upper portion 24 of the side 65 wall 14 by hinges as at 26. As a means for protecting the box against breakage during 70 shipment, the top 15 is also provided with a pair of longitudinally extending bars 27 and 28, which are arranged at the longitudinal edges of the member 15 as are the 75 bars 16 and 17 on the bottom wall 10. It 80 will be observed by reference particularly to Fig. 3, that the terminals of the bars 18, 19, 20 and 21, and 27 and 28 are extended a 85 short distance beyond the edges of the box members to which they are applied. The purpose of this extension of the members will be apparent, when reference is had to Fig. 1. By reference to this figure, it will 90 be noted that the bars of the end walls are pivoted into the members 16 and 17, and are disposed against the inner faces thereof, so that when the end walls are in assembled position, the upper terminals of the 95 bars 18, 19, 20 and 21 are arranged interiorly of the bars 27 and 28 and abut the projecting terminals thereof. This arrangement of the various bars provides two protecting rims or frames which in practice 100 have been found to adequately protect the box from breakage, such as often results from accidentally dropping the box on the floor of a freight car.

As a means for holding the end walls in 105 assembled relation to the side wall and bottom wall, when these latter are in assembled relation, there have been provided a pair of hinges 29. These hinges are located at the meeting edges of the side and end walls 110 and are identical in structure, and one of these has been illustrated in detail in Figs.

6 and 7. By reference to these figures, it will be noted that these figures include two leaf members 32 and 33 connected in the usual manner. The leaf 32 is formed with a longitudinal slot 34, while the leaf 33 is shaped to produce an L-shaped conformation forming a resultant slot 35 and a short leg 36.

Referring now to Fig. 3, it will be noted 10 that the hinge is normally fixed to the element 23 of the side wall 14 by a headed stud or screw 37 which is arranged in the slot 34 of the leaf 32. A similar stud 38 is carried by the inner face of the wall 12 and 15 is arranged to be disposed in the slot 35 of the leaf 33 when the box sections are in assembled position. It will of course be apparent that by sliding the leaves upwardly, the leaf 33 will be withdrawn from 20 engagement from the stud 38 and may be folded against the leaf 32, whereby the box elements may be folded in the manner to be next described.

As illustrated most clearly in Fig. 5, the 25 box is collapsed and arranged with its various elements in compact folded position by folding the side wall 13 on the bottom wall 10, then folding the side wall 14 to dispose the member 23 on the bottom wall 30 10, and the member 24 on the member 23. The top 15 is then folded to lie jointly on the members 24 and 13, the end walls 11 and 12 are then folded against the outer face of the bottom wall 10, and the box 35 sections are in complete folded position. A strap or other suitable fastening device may of course be passed around the box to hold the parts in the desired position.

In securing the side wall 13 and top 15 in 40 assembled position, the preferred embodiment of this invention employs a pair of latch members, each of which includes a pair of plates 39 and 40, respectively, secured to the edges of the members 15 and 13 and formed terminally with rolled ears as at 41 and 42. The plates of each latch member are arranged in staggered relation to each other, so that the rolled ears 39 and 40 are disposed in registered position. When 50 the box elements are in assembled relation, a wire or other suitable fastening device may be passed through the registered ears 41 and 42 to hold the side walls and top in desired relation.

55 The ordinary box or crate of this invention may of course be made of wood, but it has been found desirable in practice to utilize fiberoid, vulcanized fiber, match board, pantasote, or some other similar composition.

As shown in Fig. 2, the hinge fastener on the wall 14 is carried by the lower section

23 of the wall. This admits of the upper section 24 being swung outwardly with the top 15 when the latter is moved to open 65 position to admit of greater access being had to the interior of the box. The fastener 29 on the wall 13 is carried by the upper section 22^a and the stud 38, which is to be engaged by the fastener on the section 22^a, when the section is in operative 70 position, is located adjacent the upper edge of the end wall 11. By virtue of this construction the sections 22^a and 22^b and the end wall 11 will be held in operative position 75 when the top 15 is moved to open position.

In reduction to practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various 85 minor changes in details of construction, proportion and arrangement of parts may be resorted to, when required, without sacrificing any of the advantages of my invention, as defined in the appended claim. 90

Having thus described my invention, what I claim is:

The combination with a crate having folding side and end walls, studs carried by the end and side walls and located adjacent 95 the meeting edges of said walls, hinges associated with the inner surfaces of the side and end walls and positioned at the meeting edges of the said walls, and each including a pair of leaves connected to each other by 100 a pintle, one of the leaves being of substantially rectangular configuration and having a vertical slot therein for receiving the stud of the adjacent side wall, the other leaf being substantially inverted L-shaped and 105 adapted to engage the inner face of the adjacent end wall and having a downwardly extending projection formed on the shorter arm thereof, the said hinge being adapted to vertical movement on the stud carried by 110 the side wall and adapted, when the walls of the crate are in crate formation, to be slid downwardly so as to cause the downwardly extending projection on the shorter arm of the L-shaped leaf to engage over the 115 studs on the adjacent end wall, so as to hold the adjacent side and end walls in operative position.

In testimony whereof I affix my signature in presence of two witnesses.

WILLIAM R. WATKINS.
